UNITED STATES PATENT OFFICE.

WILLIAM O. GARRETT, OF MARYVILLE, MISSOURI.

STOCK-WATERING APPARATUS.

No. 810,111.

Specification of Letters Patent.

Patented Jan. 16, 1906.

Application filed May 4, 1905. Serial No. 258,824.

To all whom it may concern:

Be it known that I, WILLIAM O. GARRETT, a citizen of the United States, residing at Maryville, in the county of Nodaway and State 5 of Missouri, have invented a new and useful Stock-Watering Apparatus, of which the following is a specification.

The invention relates to improvements in stock-watering apparatus.

10 The object of the present invention is to improve the construction of stock-watering apparatus and to provide a simple and comparatively inexpensive one designed to be connected with the water-supply of a city or 15 farm and provided with means for automatically controlling the flow of water under any pressure.

A further object of the invention is to provide a stock-watering apparatus of this character in which the accumulation of sediment beneath the float of the valve will not operate to cause a leakage and consequent waste of water and in which the valve mechanism will not become inoperative and leak should 25 the apparatus get out of plumb through settling of the main casing on the platform or other part.

Another object of the invention is to enable the water within the tank or trough of 30 the apparatus to be cheaply heated sufficiently to prevent the water from freezing, whereby the apparatus is adapted to be used throughout the entire year at a very low cost.

With these and other objects in view the 35 invention consists in the construction and novel combination and arrangement of parts hereinafter fully described, illustrated in the accompanying drawings, and pointed out in the claims hereto appended, it being understood 40 that various changes in the form, proportion, size, and minor details of construction within the scope of the claims may be resorted to without departing from the spirit or sacrificing any of the advantages of the invention.

In the drawings, Figure 1 is a vertical sectional view of the stock-watering apparatus constructed in accordance with this invention. Fig. 2 is a plan view of the same. Fig. 50 3 is a horizontal sectional view. Fig. 4 is a perspective view of the lower section or heat-

ing-chamber of the main casing. Fig. 5 is an enlarged detail sectional view of the float and the valve.

Like numerals of reference designate corresponding parts in all the figures of the drawings.

1 and 2 designate upper and lower sections of a main casing which is preferably constructed of cast metal; but any other suitable material may be employed in the construction of the stock-watering apparatus, and the casing at the corners may be either round or square. The upper and lower sections are substantially rectangular in horizontal section, with the exception that the front is bowed at opposite sides of the center. The upper section, which constitutes a tank or trough, is provided with a depending flange 3 to receive or fit over the top of the lower section, which is provided with an inwardly-extending horizontal flange 4 to form a seat for the upper section. The interlocking of the upper and lower sections by means of the flange 3 prevents any water from entering the lower section from the exterior. The two sections are firmly clamped together by means of a vertical supply-pipe 5, piercing the bottoms of the sections and provided with upper and lower nuts 6 and 7 for engaging the lower faces of the said bottoms and having means for engaging the upper face of the bottom of the upper section. This means preferably consists of a valve-casing 8, having a flange 9 at the lower end forming an annular shoulder for engaging the upper face of the bottom of the upper section 1. The nuts 6 and 7 are arranged on the threaded portions of the supply-pipe, and by screwing them against the bottoms of the sections 1 and 2 the latter are firmly clamped in their interlocked relation.

The upper section is provided with a top 10, having circular openings 11, located at the bowed or bulging portions of the front and adapted to permit hogs and other animals to obtain access to the water within the upper section. The flow of water is controlled by a valve 12, movable upwardly and downwardly within the casing 8 and tapered toward its top and bottom. The valve is provided with a stem 13, and the valve-cas-

ing, which is substantially circular, is provided at the top with a valve-seat 14, arranged to receive the tapered upper portion of the valve when the same is lifted by a 5 float 15. The float is hollow and cylindrical, being provided with a central opening 16 and having an interior annular air-chamber 17, surrounding the central opening. An arched transverse piece 18 extends over the 10 opening of the float and is provided with a central aperture 19 to receive the stem 13, which is movable freely through the said opening, the movement being limited by upper and lower stops consisting of nuts 20 and 15 21. The stem is threaded to receive the nuts, which are adjustable to regulate the movement of the float independently of the valve for controlling the level of the water within the tank or trough. When the float eng- 20 gages the upper stop, it closes the valve and shuts off the flow of water, and as the water is consumed the float drops, opens the valve, and causes the water to flow from the supply- 25 pipe 5. The float and the valve are adapted to automatically control the flow of water, as will be readily understood, and any accumulation or sediment beneath the float will not operate to open the valve and cause the waste of water, but will only operate to 30 close the valve and shut off the supply of water. Also owing to the tapered form of the valve and the circular valve-casing any settling of the main casing will not affect the operation of the valve, which will operate 35 whether it is perfectly plumb or not. Also the supply-pipe may be connected with the water-supply of a city, where the pressure is heavy, or with the supply of a farm, where the water-pressure is comparatively light, and it 40 will be positive in its operation under any pressure of water.

Within the lower section or heating-chamber is arranged a heating device 22, consisting of a lamp having a burner 23 and a cylindrical oil-reservoir 24, which extends through 45 and below the bottom of the lower section of the casing and which is connected by a small supply-pipe 25 with an oil-tank 26, located beneath a platform 27, on which the 50 main casing is mounted, as clearly illustrated in Fig. 1 of the drawings. By this construction and arrangement only a small quantity of oil is within the reservoir of the lamp, and there is no danger of an explosion, and a considerable quantity of oil may be placed within 55 the oil-tank 26, so that the heating device may be left for a considerable time without attention. Any suitable means may be provided for shutting off the flow of the oil when 60 changing the wick or when removing the burner from the oil-reservoir 24 of the lamp for any other purpose. The lamp is located

beneath a tube 28, which constitutes a chimney and which is located beneath an imperforate portion of the top of the upper section 65 or casing. The chimney-tube 28, which has a threaded lower end, pierces the bottom of the upper section 1 and is provided with upper and lower nuts 29, arranged to clamp the lower end of the tube 28 tightly to the bottom of the upper section 1. 70

The lower section or heating-chamber is provided at one side with a sliding door 30, arranged in suitable guides or ways 31 and adapted to be readily opened to afford access to the interior of the heating-chamber; but any other desired construction may be employed for this purpose. 75

Having thus fully described my invention, what I claim as new, and desire to secure by Letters Patent, is— 80

1. The combination of a tank, a valve-casing extending upward from the bottom of the tank and provided with a seat, a valve operating within the casing and provided 85 with a stem extending upward from the same, a float having an opening of greater diameter than the valve-casing and resting upon the bottom of the tank when it is at the limit of its downward movement, and means 90 for loosely connecting the stem of the valve with the float.

2. The combination with a tank having a depending flange, a heating-chamber located beneath the tank and fitting within the said 95 flange, whereby it is interlocked with the tank, a heating device, and a supply-pipe piercing the heating-chamber and the tank and retaining the same in their interlocked relation. 100

3. The combination of a tank, a heating-chamber located beneath the same, a supply-pipe piercing the heating-chamber and rigidly secured to the tank, and adjustable means carried by the supply-pipe and engaging 105 the heating-chamber. 100

4. The combination of a tank, a heating-chamber located beneath the same, a supply-pipe piercing the bottoms of the tank and the heating-chamber, a valve-casing arranged on 110 the supply-pipe and engaging the upper face of the bottom of the tank, nuts mounted on the supply-pipe and engaging the lower faces of the bottoms of the tank and the heating-chamber and clamping the said tank and 115 heating-chamber together, and a valve operating in the valve-casing.

5. The combination of a heating-chamber composed of a bottom and upwardly-extending walls, one of the walls having a door, a 120 tank supported by the walls of the heating-chamber and provided with a chimney-tube fixed to the bottom of the tank, a lamp mounted within the heating-chamber and lo-

cated beneath the chimney-tube, said lamp being provided with an exteriorly-projecting reservoir, a water-supply pipe piercing the heating-chamber and the said tank and retaining the chimney-tube in position above the lamp, and means connected with the exteriorly-projecting portion of the reservoir for supplying the same with oil.

In testimony that I claim the foregoing as my own I have hereto affixed my signature ¹⁰ in the presence of two witnesses.

WILLIAM O. GARRETT.
